UNITED STATES PATENT OFFICE.

JAMES K. MILLER, OF EMPORIA, KANSAS.

SHOCK-COMPRESSOR.

SPECIFICATION forming part of Letters Patent No. 447,619, dated March 3, 1891.

Application filed October 20, 1890. Serial No. 368,685. (No model.)

To all whom it may concern:

Be it known that I, JAMES K. MILLER, of Emporia, in the county of Lyon and State of Kansas, have invented a new and Improved 5 Shock-Binder, of which the following is a full, clear, and exact description.

My invention relates to improvements in that class of binders which are used in compressing fodder and corn shocks and holding them while they are being tied, although it may also be used in compressing any other kind of bundle, if desired.

The object of my invention is to produce a binder of simple construction, by means of 15 which a shock may be quickly and easily compressed, which may be instantly released after the shock is tied, and which may be used either right or left handed and either side up.

20 To this end my invention consists in certain features of construction and combinations of parts, which will be hereinafter fully described, and then pointed out in the claims.

Reference is to be had to the accompanying 25 drawings, forming part of this specification, in which similar letters of reference indicate corresponding parts in all the figures.

Figure 1 is a perspective view of the binder with a rope attached, showing the position of 30 the binder and rope when the shock is bound. Fig. 2 is an inverted plan view of the binder. Fig. 3 is a plan view of the same, and Fig. 4 is a side elevation of the binder.

The binder is preferably made of hard wood, 35 although metal may be used in its construction, if desired, and it comprises a handle A, which is located at one end, and which terminates in a central body portion B, which is split longitudinally to form the two opposite 40 arms B' and B'', between which is pivoted a grooved pulley C. Both the arms B' and B'' project beyond the pulley; but the arm B' is prolonged to form the head B³, the outer side of the arm B' being beveled, as shown at b 45 near its opposite edges, and the arm B' is cut away and rounded slightly beyond the outer portion of the pulley C to form the neck b', which facilitates the removal of the binding-rope from the pulley and enables it to be 50 easily belayed.

The outer end of the neck b' terminates

abruptly in the shoulders b², which form the inner end of the head B³ and which insure the requisite amount of leverage on the binder to hold the free end of the rope when 55 it is belayed. The head B³ is rounded at its outer extremity, as shown, and is provided with a transverse hole b³, which enables the binding-rope D to be attached to the head, the rope being preferably passed through the 60 hole and tied into a knot, as shown in Fig. 1.

The arm B³ terminates opposite the neck b' of the arm B', and the outer end of the arm B³ is concaved, as best shown in Figs. 2 and 3, thus forming retaining-shoulders b⁴ at 65 the outer corners of the arm. These shoulders hold the free end of the binding-rope and catch under a portion of the rope, and thus prevent the binder from rolling.

The operation is as follows: The head B³ is 70 thrust into the side of the shock so as to hold the binder in place while the free end of the rope is being carried around the shock; or, if desired, the operator may hold one end of the rope D and throw the binder around the shock. 75 Then the binder is taken in the left hand, with the arm B' on the upper side, the rope D is placed on the pulley C, and the rope drawn until the shock is sufficiently compressed. The handle A is then swung to the 80 left, thus throwing the rope off the pulley onto the neck b' of the arm B'. The free end of the rope is then carried up around the neck b' above the pulley and down between the retaining-shoulders on the arm B³, and 85 finally the handle is swung to the right and the projecting shoulder on the right side of the arm B³ is thrust under the rope D to prevent the binder from rolling. The strain of the binding-rope D upon the binder securely 90 holds the free end of the rope between the shoulders b⁴ and the main portion of the rope which bears upon the free end, a bight being 95 thus formed which securely belays the rope. The manner in which the rope is belayed is clearly shown in Fig. 1. To release the binder after the shock is tied, the handle A is merely 100 swung to the left, thus releasing the strain of the rope D upon the free end thereof, and the device can be removed.

From the foregoing description it will be seen that the neck b' on the opposite shoul-

ders on the arm B^3 enable the binding-rope to be easily belayed, as the shoulders b^2 of the head B^3 prevent the rope from slipping from the binder, and the shoulders b^2 of the head B^3 insure a definite amount of leverage on the binder to hold the free end of the rope when it is belayed. The binder may be made of any desired size.

Having thus fully described my invention, I claim as new and desire to secure by Letters Patent—

1. A shock-binder comprising a handle, a central body portion split longitudinally to form two arms, one of which is prolonged and formed into a narrow neck and a terminal head, and a pulley pivoted between the arms, the head being apertured to receive a rope, substantially as described.

2. A shock-binder comprising a handle, a central body portion split longitudinally to form two arms, one of which is prolonged and formed into a narrow neck and a terminal head, a pulley pivoted between the arms, and a rope attached to the head, substantially as described.

3. A shock-binder comprising a handle, a body portion connected therewith, said body portion being split longitudinally to form opposite arms, one of the arms being prolonged and formed into a narrow neck, a terminal head having a transverse hole therein, a binding-rope attached to the perforated head, and a pulley pivoted between the arms, substantially as described.

4. A shock-binder comprising a handle, a body portion connected therewith, said body being split longitudinally to form opposite arms, one of the arms being rounded and reduced to form a neck, and then enlarged to form a terminal head, and the opposite arm being concaved at the end, forming retaining-shoulders at the outer corners, a pulley pivoted between the two arms, and a binding-rope attached to the enlarged head, substantially as described.

JAMES K. MILLER.
